UNITED STATES PATENT OFFICE

153,823

DESIGN FOR A FLEXIBLE CABLE LOCK

Edward G. Reese, Landisville, and Gerald B. Fenstermaker, Lancaster, Pa., assignors to Reese Padlock Company, Lancaster, Pa., a co-partnership

Application December 8, 1947, Serial No. 143,040

Term of patent 14 years

(Cl. D50—7)

To all whom it may concern:

Be it known that we, Edward G. Reese and Gerald B. Fenstermaker, citizens of the United States, residing at Landisville and Lancaster, respectively, in the county of Lancaster and Commonwealth of Pennsylvania, have invented a new, original, and ornamental Design for a Flexible Cable Lock, of which the following is a specification, reference being had to the accompanying drawing, forming part thereof.

In the accompanying drawing:

Figure 1 represents a rear elevation of a lock, showing our new design;

Figure 2, a side elevation thereof;

Figure 3, a front elevation thereof; and

Figure 4, a bottom plan view thereof.

In each of Figures 3 and 4 the flexible cable is shown fragmentarily for convenience in illustration.

We claim:

The ornamental design for a flexible cable lock, substantially as shown and described.

EDWARD G. REESE.

GERALD B. FENSTERMAKER.
